(57) **CLAIM**

The ornamental design for a disposable sheet, as shown and described.

DESCRIPTION

FIG. 1 is a perspective view illustrating the disposable sheet, constructed in accordance with the teachings of the present invention.

FIG. 2 is a top plan view of the disposable sheet of FIG. 1; and,

FIG. 3 is a bottom plan view of the disposable sheet of FIG. 1.

The broken lines indicate that the central surface within the broken lines is understood to be of indeterminate length and width, it being further understood that the pattern repeats uniformly throughout its length and width.
